UNITED STATES PATENT OFFICE.

WALTER J. CONLON, OF CHICAGO, ILLINOIS.

WASHING-MACHINE GEARING.

Application filed April 21, 1915, Serial No. 22,760. Renewed August 23, 1920. Serial No. 405,487.

To all whom it may concern:

Be it known that I, WALTER J. CONLON, a citizen of the United States, residing at Chicago, in the county of Cook and State 5 of Illinois, have invented certain new and useful Improvements in Washing-Machine Gearing, of which the following is a full, clear, concise, and exact description, reference being had to the accompanying drawings forming a part of this specification.

My invention relates to washing machines and is particularly concerned with that type in which a reversing movable element is employed. It is the object of my invention to provide a generally improved structure which will be of economical manufacture, of simple design and of effective operation, one of the primary objects being the provision of an operative structure which 10 will not incur the shock which is generally felt in machines of this type in which reversing elements are employed. More specifically, my invention has to do with a washing machine which employs a rotating drum—a drum which operates for a few revolutions in one direction and then for a few revolutions in the other direction, and so on. Obviously, at the end of each operation in a given direction there will be a considerable and detrimental shock unless something is provided to compensate for it, and thus this purpose of my invention will be appreciated. Generally, I may say that my invention has to do with the driving of this 15 washer shaft, and various points of novelty will be brought out hereinafter and definitely pointed out in the appended claims.

In the drawings—

Figure 1 is a front elevational view of 20 a machine embodying my invention, certain of the parts being broken away to show the driving mechanism for the washing drum.

Figure 2 is a side elevational view of 25 the same with certain of the parts broken away.

Figure 3 is a detail view on the line 3, 3, of Figure 1, showing a construction of the mechanism for reversing the rotation of the drum.

Figures 4 and 5 are fragmentary detail 30 views of the driving mechanism for the drum.

Figure 6 is a front view with a part broken away of the shock absorbing friction clutch between the motor shaft and the automatic reversing mechanism.

Figure 7 is a cross-section of the same.

Figure 8 is a rear elevation of the outer clutch member.

Figure 9 is a view of one of the friction 35 discs.

Figure 10 is a view of a cooperating friction disc, and

Figure 11 is a view of the inside clutch 40 member.

The machine comprises a combined washing and wringing machine, having a washing drum 20 and wringer rolls 21 which are driven by the electric motor 22. The drum 20 is enclosed in a suitable casing 23 having a semi-circular bottom portion and a rectangular top portion, and provided with a hinged cover 24 which is preferably made of sheet metal. This cover is composed of two parts hinged at 25 and attached to the casing 23 by the hinge 26, to allow the cover to be moved out laterally to disengage the various projecting parts of the machine when the cover is removed. The washing drum 20 is provided with a 45 removable gate 18 held by a catch 19, for allowing ready access to the interior of the drum.

The various parts of the machine are supported by the legs 27 which are bolted to the 50 casing 23 and which in connection with the casing form a framework for the other parts. Pivoted rollers are provided to allow the machine to be readily moved from place to place. The washing drum 20, shown in dotted lines in Figures 1 and 2, 55 substantially fills the casing 23 and, when the machine is in operation, this drum 20 contains the articles which are to be washed and the casing 23 contains the washing liquid into which the drum is partially submerged.

In a machine of this character, it is desirable that the washing drum be rotated a number of times in one direction and then in the opposite direction the same 60 number of times to prevent wadding of the clothes into a compact mass inside of the drum 20. I secure this effect by the use of automatic reversing mechanism of

the type disclosed in Patent No. 1,077,748. granted to Thomas H. Phillips, Jr., on November 4, 1913.

On the end of stub shaft 28 is pinned a squared drive member 39 that fits into a corresponding socket member 39' which is attached to the drum. This allows the ready attachment and detachment of the driving shaft and the drum so that the drum 20 can readily be taken out of the casing 23 when so desired. A bevel gear 29 is attached to the outer end of shaft 28. This gear is driven for a definite number of revolutions in one direction of rotation indicated by the light arrow and is then driven in the opposite direction as indicated by the heavy dotted arrow, an equal number of revolutions.

The shaft 30, which is constantly driven by the motor 22 in one direction of rotation, bears two loosely mounted bevel pinions 31 and 32 which mesh with the bevel gear 29 at all times. A spacing sleeve 33 is rigidly attached to the shaft 30 and serves both to hold the bevel pinions in place and to transmit power intermittently to one and then the other of these pinions. This is accomplished by means of a bar 34 pivoted on a pin 35. The pin is mounted in two lugs 36 between which a groove is formed for the reception of bar 34. This bar 34 has only a limited play as the ends thereof strike against the bottom of the groove between the lugs 36. The outer ends of the bar 34 are adapted to engage at times the pins 37 and 38 mounted on the bevel gears 31 and 32, but, due to its pivotal mounting, only one end of this bar is able to engage one of these pins at a time.

In Figure 4, the bar 34 is shown as being in contact with the pin 37 on the bevel gear 31. As the shaft 30 is constantly driven in one direction of rotation, as indicated by the light arrow, the sleeve 30, which is connected to said shaft, will drive the gear 31 because of the engagement of the bar 34 to the pin 37. The bevel pinion 32 revolves idly in mesh with the gear 29 at this time. After the gear 29, which is attached to the drum 20, has revolved a predetermined number of times in one direction, the bar 34 is swung about its pivot 35 to disengage the pin 37 and to engage the pin 38. This allows the gear 31 to be idle and the gear 32 to transmit power and thus drive the bevel gear 29 in the opposite direction of rotation as shown by the heavy dotted arrow. The tilting of the bar 34 is accomplished automatically by means of the pin 40. When the proper number of revolutions has been performed to bring the pin 40 within the radius of the end of the bar 34, pin 40 and the bar 34 will come in contact and, by a movement in the nature of a rolling motion, the end of the bar 34

will be forced inwardly to disengage the pin 37, but will have its other end raised to lie within the path of the pin 38 on bevel gear 32 and as the shaft 30 continues to revolve the bar 34 will engage the pin 38 and drive the gear 29 in the opposite direction.

To maintain the lever 34 positively in each position and to prevent any shifting except by action of pin 40, a mechanism is provided for giving a snap motion from one position to the other. This is accomplished by means of the pins 41 which are attached to the flat spring 42 mounted on the side of the lug 36. Sockets are provided in the bar 34 into which the pins 41 are forced by the spring 42 to give the bar 34 a snap action. The ends of the pins 41 are preferably rounded or tapered. The pins 37 and 38 are angularly displaced relatively to the bar 34 so that, when the bar is snapped out of engagement with one of the pins, the shaft 30 will turn part of a revolution before the bar engages the other pin. This gives the drum connected to the bevel gear 29 time to slow down and it may even come to rest and, thus, jarring or straining of the mechanism, which would occur in overcoming inertia of the moving drum, if its movement were immediately reversed, is obviated.

In operating the machine, it has been found that the clothes will sometimes cling to the sides of the drum 20 and will tend to rotate the drum ahead of the driving means. This moves the pinion ahead of the driving bar 34 and when the bar overtakes the pin 37 or 38, it engages the pin with considerable jar and shock in again starting the drum to revolve. This action would also occur if the machine were run idly. The inertia of the drum is considerable and when the bar engages the pin to start the drum the shock causes the drum to rebound and to run ahead of the driving means.

This running ahead or rebounding is very undesirable, being noisy and disagreeable as well as being dangerous to the mechanism. Special means in the shape of a latch is provided to prevent such action. The latch comprises a bevel pin 43 passing through a hole in the web of the pinion and pressed inwardly by spring 44. In action the bar 34 passes over the beveled end of the pin 43 to come into engagement with one of the driving pins 37 or 38 and is then held between the driving pin and the latch pin until this bar 34 is snapped out of engagement with both pins by the action of the pin 40.

To supplement the action of the reversing mechanism, a shock absorber 46 has been introduced in the driving connections for the washing drum. This shock absorber, which

consists of a multiple disc clutch, is mounted in the hub of the gear 50. A detailed description of this clutch will be given later in connection with Figures 6 and 11. The 5 positive gripping action caused by the latch 43 does not entirely obviate the difficulties imposed upon the transmission mechanism, but the shock absorbing clutch 46 supplements this action so that a very satisfactory 10 transmission is secured.

The bearings for the shafts 28 and 30 are provided in the bracket casting 45 which is bolted to the casing 23 and the legs 27. The casting also forms a support for the motor 15 22 which drives the power shaft 30. The shaft 30 is driven through the bevel gears 50 and 51 from the main shaft 52, which is connected to the motor shaft by means of the gear wheel 53 and a worm 54 mounted on 20 the extension of the motor shaft.

The bevel pinion 51 is loosely mounted on the shaft 52 and is adapted to be clutched to said shaft only when it is desired to actuate the drum 20 of the washing machine. An 25 extension 55 of the shaft 52 is connected through gears to the wringer rolls 21. The clutch for throwing the washing mechanism in and out of gear comprises a projection 56 mounted on the pinion 51 and a projection 30 57 mounted on the sliding sleeve 58. This sleeve is keyed to the shaft 52 and, when shifted into the lower position where the projections 57 and 56 engage each other, power is transmitted to the washing mechanism. The sleeve 58 is provided with a 35 groove into which a U-shaped shifting fork 59 is fitted.

A rod 60 connected to a lever 61 is adapted to shift the clutch member 58 and thereby to connect or disconnect the washing mechanism from the main driving shaft.

The connection between the rod 60 and the lever 61 is enclosed in the housing 63 which also encloses the control mechanism for the wringer. Since my present invention is not concerned with this control mechanism I shall refrain from going into a detailed description here, but shall now proceed with the description of the friction clutch mechanism.

The friction clutch 46 is shown in detail in Figures 6 to 11. It consists essentially of an outer clutch member 110, which is formed preferably at an extension of the hub of the gear wheel 50, an inner clutch member 111, with a plurality of friction discs cooperating with the clutch members. Alternate ones 55 112 of these discs are connected with the outer clutch member. The other discs 113 are connected with the inner clutch member and rotate therewith. The flange 115 of the member 110 has slots 116 cut lengthwise at symmetrical points on its circumference. Teeth or projections 117 formed on the outer edge of 60 members 112 are adapted to fit into these

slots and to have positive engagement therewith. The discs 113, which alternate with the discs 112, have teeth 118 formed on their inner edge. These teeth are adapted to have positive engagement with the grooves 120 70 formed on the hub of the inner clutch member. It can thus be seen that alternate ones of the discs are connected with one clutch member and the others are connected with the other clutch member. Pressure is applied to the discs by means of the screws 121 and the pressure or face plate 122 which bears against the end of the outer clutch member 110. The clutch may be tightened or loosened as found desirable by adjusting 80 the screws 121. The inner clutch member 111 is provided with a rectangular bore which receives the squared end of the shaft 30. The friction clutch serves a double purpose in the present structure. It serves as a 85 friction clutch for the motor and prevents the motor being stalled and burned out, and it serves also as a shock absorber for the reversing mechanism to give a smooth reversal of motion.

A brief description of the operation of the mechanism illustrated will now be given:

The drum 20 is opened by means of a gate indicated in Figure 3 and the clothes are placed inside the drum. The casing 23 is 95 then partially filled with washing water. The gate of the drum is closed and the cover 24 is closed and the machine is ready for the washing operation.

Current is supplied to the electric motor 100 to drive the power shaft 52. The handle 61 shown in Figure 2 is moved to a lower position to throw the clutch mechanism for the washing drum into engagement with the power shaft. The shaft 30 transmits motion to the gear 29 and to the washing drum 20, first through one of the bevel pinions and then through the other, by the operation of the automatic reversing mechanism. After the clothes have been sufficiently washed, the 110 lever 61 is moved to the upper position to disengage the washing clutch mechanism. The cover 24 may be raised and the drum 20 opened to give access to the washed articles.

I claim as new and desire to secure by Letters Patent:

1. A device of the class described comprising a driving shaft, a driven shaft, a pair of facing bevel gears loosely mounted 120 on one of the shafts, a bevel gear meshing with said facing gears and rigidly secured to the other shaft, a sleeve on the shaft intermediate said facing gears and rigidly secured to said shaft, a pivoted member on 125 said sleeve, means on said bevel gear meshing with said facing gears for causing said member on said sleeve to engage alternately each of said facing gears after a predetermined number of revolutions, and latch 130

mechanism for engaging said member adjacent its end.

2. A device of the class described comprising a driving shaft, a driven shaft, a pair of facing bevel gears loosely mounted on one of the shafts, a bevel gear meshing with said facing gears and rigidly secured to the other shaft, a sleeve on the shaft intermediate said facing gears and rigidly secured to said shaft, a pivoted member on said sleeve, means on said bevel gear meshing with said facing gears for causing said member on said sleeve to engage alternately each of said facing gears after a predetermined number of revolutions, and latch mechanism 15 on said sleeve and also on said facing gears

for holding said member in each of its positions.

3. In combination, a driving shaft, a pair of loose pinions on said shaft, a driven shaft 20 having a gear meshing with said pinions, a member pivoted within its length and mounted to rotate with the driving shaft, the ends of said member being adapted to clutch the pinions alternately to the driving shaft, 25 and latch mechanism arranged to engage each end of said member for holding the member in clutching engagement with the pinions.

In witness whereof, I hereunto subscribe 30 my name this 13th day of April, A. D. 1915.

WALTER J. CONLON.
